UNITED STATES PATENT OFFICE.

ALEXANDER F. BUCHANAN, OF MONTROSE, NEW YORK.

MACHINE FOR ORNAMENTING AND CUTTING OIL-CLOTH, &c.

SPECIFICATION forming part of Letters Patent No. 271,782, dated February 6, 1883.

Application filed October 24, 1882. (No model.)

To all whom it may concern:

Be it known that I, ALEXANDER FORDYCE BUCHANAN, a citizen of the United States, residing at Montrose, in the county of Westchester and State of New York, have invented new and useful Improvements in Machines for Ornamenting and Cutting Oil-Cloth, &c., of which the following is a specification.

This invention consists in a machine in which a web of oil-cloth, paper, or other like material is cut in a zigzag, undulating, or other analogous plane, and ornamented or decorated on opposite sides of the cut in a plane parallel therewith, as hereinafter more fully set forth.

This invention is illustrated in the accompanying drawings, in which Figure 1 represents a vertical cross-section. Fig. 2 is a side view of the cutting-roller. Fig. 3 shows a portion of the cut and ornamented web.

Similar letters indicate corresponding parts.

The letter A designates the machine-frame, forming the bearings for a cutting-roller, B, and decorating-roller C, one provided with a circumferential knife, E, extending in a zigzag, undulating, or other similar plane, and the other provided with circumferential printing or embossing devices in two sets, which extend in a plane parallel to each other and to said knife, on opposite sides of the knife.

The rollers B C are geared, as by means of cog-wheels F, in such a manner that the printing or embossing devices composing the acting surface of the decorating-roller register with said knife of the cutting-roller relatively to the web brought in contact therewith, as presently explained, and each of such rollers bears against a pressure-roller, G or H, which is mounted in the machine frame in the proper manner. The web of oil-cloth or other like material is conducted from a roll, I, over guide-rollers J J', between the cutting-roller B and its pressure-roller G, thence between the decorating-roller C and its pressure-roller H, and finally over a

drying-roller, K. By the action of the roller-knife E the web is cut or severed in a plane 45 corresponding to that of the knife, while by the action of the decorating-roller C it is printed or embossed on opposite sides of and parallel with the cut, as indicated in Fig. 3, and hence the web is divided into two parts or 50 lengths, each of which has a scalloped edge, in addition to a line of ornamentation corresponding to such edge, without waste of material. For the purpose of imparting to said divided lengths of the web a good finish the cutting-roller is provided with trimming-knives L', which act on the web at or near its opposite longitudinal edges in its passage over the cutting-roller.

If desired, the roller-knife E may be arranged to score the web, without cutting it, a sufficient distance in each revolution of the roller to leave the parts of the web united to each other, while the cutting-roller and decorating-roller, moreover, may be transposed, so 65 that the web is first printed or embossed and then cut.

What I claim as new, and desire to secure by Letters Patent, is—

The combination, substantially as hereinbefore described, of the cutting-roller having a circumferential knife extending in a zigzag, undulating, or other similar plane, the decorating-roller having the devices composing its acting surface arranged on opposite sides of 70 said knife of the cutting-roller to register therewith, and the pressure-rollers co-operating with the cutting-roller and decorating-roller, respectively, for the purpose specified.

In testimony whereof I have hereunto set my 80 hand in the presence of two subscribing witnesses.

ALEXANDER FORDYCE BUCHANAN.
